UNITED STATES PATENT OFFICE.

JESSE ALEXANDER, OF BROOKLYN, NEW YORK, ASSIGNOR, BY MESNE ASSIGNMENTS,
OF ONE-HALF TO EMMA SCHEU SCHORCHT, OF BUFFALO, NEW YORK.

TYPE-WRITER LINE-SPACING MECHANISM.

974,333.

Specification of Letters Patent.

Patented Nov. 1, 1910.

Application filed October 8, 1908. Serial No. 456,806.

To all whom it may concern:

Be it known that I, JESSE ALEXANDER, citizen of the United States, residing at Brooklyn, county of Kings, State of New York, have invented certain new and useful improvements in Type-Writer Line-Spacing Mechanism, of which the following is a full, clear, and exact description.

My invention relates to line spacing mechanism for typewriters.

This application is filed in place of applicant's abandoned applications 130,550, filed Nov. 8, 1902, and 340,637, filed October 26, 1906.

15 In the accompanying sheet of drawings Figure 1 is a plan view of those parts of a typewriting machine involving the improvements of my invention. Fig. 2 is a front elevation of the same. Fig. 3 is a rear elevation of the same. Fig. 4 is a view of the left-hand end of the carriage construction and the supporting frame of the machine and illustrating the application of my invention.

25 In these drawings, 1 indicates a fragment of the frame of the machine of suitable construction.

2 is a member of the carriage construction which is adapted to move laterally across the machine. 3 is another member 30 of the carriage construction called a side plate.

4 indicates a fragment of a suitable rotary platen. 5 is the shaft therefor which 35 has bearings in the side plate 3 at the left-hand end of the machine and in a similar side plate at the right hand end of the machine.

6 is a suitable knob or handle for manually turning the platen.

The carriage has an integral upwardly projecting post 7 suitably curved and formed on the left-hand outer surface for digital engagement for the purpose of moving the carriage from the left-hand side of the machine to the right.

8 is a crown ratchet carried by the platen at the left-hand end.

9 is a spring-pressed roller carried by the 50 carriage and engaging with the teeth of the ratchet for holding the platen in definite line positions.

10 is an operating lever suitably formed on its forward end for digital engagement 55 and having a vertical axis.

11 is a pawl pivotally carried on a vertical axis by the operating lever 10 and adapted to be thrown into engagement with the teeth of the ratchet when the operating handle is moved to the right. 6

12 is an adjustable stop secured in the carriage side plate which engages the rear end of the pawl 11 when the operating handle is moved to the left and rests against the carriage side plate as shown particularly in Fig. 1. This stop throws the pawl out of engagement with the teeth of the ratchet so that the ratchet is free to be moved in either direction by hand.

13 is a spring-pressed stop pivotally mounted and having a handle 14. 15 is a spring for returning the operating lever to its normal position. This stop is adapted to be adjusted and acts to limit the movement of the operating lever and consequently the pawl 11. The rearwardly projecting portion of the operating lever engages this stop on the backward movement. The extent of movement of the pawl, consequently the amount of rotation of the platen, is determined by the position of the adjustable stop. 80

By reason of the position of upright post 7 and operating lever 10, the parts are adapted for quick and convenient operation, it being possible to apply one part of the 85 hand to the post 7 for moving the carriage and then during the same movement to apply another part of the hand or finger to the operating lever for the purpose of spacing. The advantage of this construction 90 will be apparent to those skilled in the art,

What I claim is:—

1. A line-spacing mechanism for a typewriter including a rotatable platen having a horizontal axis; a crown ratchet-wheel movable therewith, a horizontally movable operating-lever mounted on a vertical axis, a pawl pivoted to said lever forward of its axis and also having a vertical axis, a stop for normally holding said pawl out of engagement with said ratchet and a spring for moving said pawl into engagement with said ratchet when said lever is operated and said pawl is released from its stop. 95

2. A line-spacing mechanism for a typewriter including a platen, a ratchet, a carriage side-plate affording a bearing therefor, an upwardly projecting portion rigidly carried by said side-plate and adapted for digital engagement, an operating-lever 100

105

110

pivottally mounted on a vertical axis and having a forwardly projecting handle portion adapted for digital engagement, a pawl carried by said lever normally disengaged from said ratchet but adapted to rotate said ratchet when operated by said lever and an adjustable stop mounted on a vertical pivot for limiting the operative movement of said pawl.

JESSE ALEXANDER.
